Oscar Geier

UNITED STATES PATENT OFFICE.

ANTHONY J. SMIELINSKI, OF CLEVELAND, OHIO.

TIE-PIN RETAINER.

1,205,488.

Specification of Letters Patent. Patented Nov. 21, 1916.

Application filed May 26, 1916. Serial No. 99,933.

To all whom it may concern:

Be it known that I, ANTHONY J. SMIELINSKI, a subject of the Czar of Russia, and a resident of Cleveland, in the county of 5 Cuyahoga and State of Ohio, have invented certain new and useful Improvements in Tie-Pin Retainers, of which the following is a specification.

This invention relates to improvements in 10 devices for securing and protecting pins of an ornamental nature, such as are used in connection with neck-ties, headwear, and the like.

The principal object of the invention is to 15 provide means whereby the point of the pin is protected against injury to itself, or injuring articles or persons with whom it may contact.

A second object of no less importance is to 20 provide means whereby the pin is positively locked against withdrawal when once the keeper has been affixed to it.

These objects are attained by the novel 25 construction and combination of parts herein- after described and shown in the accom- panying drawing, in which:—

Figure 1 is a perspective view of the pin, showing the application of the invention. Fig. 2 is an enlarged perspective view of 30 the keeper with the end of the pin entered therein, and Fig. 3 is a vertical sectional view taken on line 3—3 of Fig. 1.

In the drawing, the pin shaft or shank 10 is provided with a head 11 which may be 35 of any preferred design the pin terminating in a point 12 containing a central longitudinal aperture 13 formed by swaging, milling or other mechanical means; the keeper or sheath 15 may be of any preferred form, 40 having a transverse cross bar 16 at the top and curved point 17 at the bottom. This keeper may be made of any preferred material, the walls inclosing a space 18 into which the pin shaft 10 enters through an 45 opening 19 in the bar 16 near one of its sides; attached to the opposite side is a wire 20 extending downward near the bottom 17, where it is formed into a spring loop 21, the extended end being coiled at 22, 50 further extended at 23 to a final coil 24, from which extends an arm 25 outturned at 26, and having secured to it a knob 27 beyond the wall of the keeper.

The coils 22 and 24 are screw-threaded in- 55 ternally, and adapted to receive the threaded

shank 30 of the anchor element 32, the head of which is flattened and adapted to enter the elongated opening 13 formed near the point of the pin shaft under normal conditions.

In operation, the keeper is passed over the point of the pin until the opening 13 is entered below the bar 16, and then turned slowly until the anchor head 32 engages within the slot or aperture under the pres- 65 sure of the spring.

In order to remove the pin shank from confinement, pressure is applied to the knob 27 whereupon the anchor is pressed out of the slot releasing the pin.

In certain forms of pins it is desirable to engage the opening at relative distances, with respect to the head, and for that purpose adjustment is provided by the threaded shank 30, so that the head 32 may engage 75 with the aperture 13 either immediately below the bar 16, or at a point nearer the bottom 17.

Obviously, the pin is held locked under the pressure of the spring in a firm and se- 80 cure manner, so that the same may not turn or be pulled outwardly under any possible pressure except such as may cause rupture of the parts.

It will be further evident that the keeper 85 may be made in other forms and ornamented to any extent desired.

Having thus described my invention, what I claim as new, and desire to secure by Letters Patent, is:—

The combination with a pin having an elongated slot formed therethrough near the point end thereof, of a keeper adapted to receive said pin including the point and mentioned slot, a spring element secured within the said keeper, a spring loop formed in said element; a plurality of eyes formed in the free end of said element, said eyes being screw-threaded, an anchor having a stem suited to said eyes whereby it may be ad- 95 justed longitudinally, said anchor being adapted to enter the mentioned slot and held normally therein by said spring element, and means extending through the walls of said keeper for releasing said anchor.

Signed at Cleveland, in the county of Cuyahoga, and State of Ohio, this 15th day of May, 1916.

ANTHONY J. SMIELINSKI.
